SASH HOLDER

Filed Aug. 7, 1925

INVENTOR.
STANLEY BARNES,

BY

Geo. B. Schley,
ATTORNEY

UNITED STATES PATENT OFFICE

STANLEY BARNES, OF INDIANAPOLIS, INDIANA, ASSIGNOR TO BARNES SASH HOLDER, INC., OF INDIANAPOLIS, INDIANA, A CORPORATION OF INDIANA

SASH HOLDER

Application filed August 7, 1925. Serial No. 48,698.

It is the object of my invention to produce a window sash holder which may be attached to the slideable sashes of windows and which will permit them to be moved up or down as desired and will retain them in any desired position without the necessity of having the customary balance weights. A further object of my invention is to include in such a sash-holder a lock which will prevent the opening 10 of the window from the outside.

I accomplish the above objects by mounting in the side of a window sash a roller-supporting member the rollers of which are spring-pressed into engagement with the window casing with sufficient pressure to retain the sash in any desired position; and I provide my sash-holder with a locking device in the form of an eccentric cam which may, when desired, be spring-pressed into engagement 20 with the window casing to prevent opening of the window.

The accompanying drawing illustrates my invention: Fig. 1 is a fragmental elevation of a pair of window sashes and their associated casing, the sashes being equipped with a device embodying my invention; Fig. 2 is a fragmental longitudinal section through the window sash showing details of my device; and Fig. 3 is a fragmental end elevation of the window sash showing further details of construction.

I have shown my invention as applied to the upper sash 10 and the lower sash 11 of a window, both sashes being vertically slideable in a window casing 12. For simplicity but one end of each sash is shown, as it will be understood that the other end of each sash will correspond to that shown. The vertical end faces of the sashes 10 and 11 are provided with recesses for the reception of my sash-holder, the various parts of which are supported from a plate 13 which bridges the recesses in each sash and is affixed to the sash by suitable screws 14.

Passing through the plate 13 is a screw 15 which extends into the recesses in the sash and slidably supports a member 16, preferably of channel cross-section. Between the two legs of the channel are rotatably mounted 50 rollers 17 adapted to engage the window cas-

ing 12. Between the member 16 and a nut 18 on the end of the screw 15, I provide a compression spring 19 which acts to hold the rollers 17 firmly in engagement with the window casing 12. Preferably, the two ends of the spring 19 are bent so as to extend for a short distance parallel to the screw 15, one of such bent ends, the end 20 as shown, engaging a hole in the member 16, and the other end, the end 21 as shown, being arranged to engage one face of the nut 18. This arrangement of the spring prevents rotation of the nut 18 and thus makes it possible to adjust the tension of the spring 19 by rotating the screw 15.

Pivotedly mounted between two ears 25 which extend inwardly from the inner face of the plate 13 is a cam 26. Rigid with the cam 26 is an arm 27 to which is affixed one end of a tension spring 28, the other end of which is attached to an arm 29 extending inwardly from the plate 13. The cam 26 is provided with a square axial recess 30 for the reception of a square key 31 by which the cam may be rotated either into or out of engagement with the window casing 12. The arm 27 is so angularly located relative to the center of the eccentric cam 26 that the spring 28 crosses the axis of pivotal mounting of the cam 26 when the cam is rotated between its two limits of movement. Thus, the spring 28 operates to hold the cam firmly in engagement with the window casing when the cam is in the full line position shown in Fig. 2 or to hold it out of engagement when in the dotted line position.

With the cam 26 in the full line position shown, upward movement of the sash 11 is prevented by reason of the tendency of the cam 26 to rotate in a counter clockwise direction and thus to become wedged against the casing 12.

Preferably, the screw 15 is slightly smaller in diameter than the hole in the plate 13 through which it passes in order to permit a slight oscillation of the screw 15 and member 16. The provision for this oscillation insures that the two rollers 17 will bear with equal force against the casing 12.

With the lock-cam 26 disengaged from the casing 12, the sash 11 may be raised or

lowered as desired. When moved to the desired position, the friction of the spring-pressed rollers 17 is sufficient to retain the sash in any location.

5 The sash holder provided for the upper sash 10 may be substantially the same as that mounted in the lower sash, but I have illustrated it as slightly modified in order to facilitate adjustment of the spring. In this 10 modification, the plate 13 is provided with a depressed center portion 40 which has a threaded opening for the reception of an adjusting screw 41. A coil spring 42, similar to the spring 19, acts between the head of the 15 screw 41 and the member 16. A hole 43 is provided leading from the bottom of the recess in the sash to the inner side of the sash. A screw-driver may be inserted through this 20 hole to adjust the tension of the spring 42 by rotation of the screw 41 without the necessity for removing the sash from the casing. The depressed central portion 40 in the plate 13 makes possible the projection of the threaded 25 end of the screw 41 without danger of its interfering with the raising and lowering of the sash 10.

I have described my device as applied to windows having wooden sashes, but it will be obvious that it is equally applicable to metal- 30 sash windows. When attached to such a window, the plate 13 may be incorporated as a part of the sash construction and need not be a separate plate.

I claim as my invention:—

35 1. In combination with a window sash and its associated casing, the end face of such sash being provided with a recess, a plate bridging such recess and secured to said sash, a member located in such recess, a screw passing inward through said plate and said member, a nut on the inner end of said screw, rollers 40 rotatably mounted on said member on opposite sides of said screw and adapted to engage said casing, and a coil spring surrounding 45 said screw and acting between said nut and said member for forcing said rollers into engagement with said casing, the ends of said coil spring engaging said member and said nut to prevent relative rotation between 50 them.

55 2. In combination with a window sash and its associated casing, the end face of such sash being provided with a recess, a plate bridging such recess and secured to said sash, a member 60 located in such recess, a screw passing inward through said plate and said member, a nut on the inner end of said screw, rollers 65 rotatably mounted on said member on opposite sides of said screw and adapted to engage said casing, and a coil spring surrounding 70 said screw and acting between said nut and said member for forcing said rollers into engagement with said casing, said screw being loosely supported in said plate so that it 75 can move angularly relatively thereto.

3. A sash holder, comprising a plate, a screw rotatably mounted in said plate, a nut on said screw, a member slidably mounted on said screw, a coil spring surrounding said screw and acting between said nut and said member, and rollers carried by said member on opposite sides of said screw, said plate being provided with openings for the reception of said rollers, the ends of said coil spring 75 engaging said member and said nut to prevent relative rotation between them.

4. An inaccessible spring tensioning means comprising an abutment element, a bolt having its shank extending therethrough and forwardly and rearwardly thereof, a spring mounted on said shank rearwardly of said element; the forward terminal portion of said spring engaging in said element to hold the spring from rotation, a nut mounted on said shank rearwardly of said spring, and a projection carried by the rear end of the 80 spring and engaging the nut to prevent rotation of the latter relative to the spring.

5. An inaccessible spring tensioning means comprising an abutment element, a bolt having its shank extending therethrough and forwardly and rearwardly thereof, a spring mounted on said shank rearwardly of said element, the forward terminal portion of said spring engaging in said element to hold the 85 spring from rotation, a polygonal shaped nut mounted on said shank rearwardly of said spring, and a projection carried by the rear end of the spring and engaging one side 90 of the nut to prevent rotation of the latter 95 relative to the spring.

In witness whereof, I have hereunto set my hand at Indianapolis, Indiana, this 31st day of July, A. D. one thousand nine hundred and twenty five.

105 STANLEY BARNES.
